(57) **CLAIM**

The ornamental design for an electric spin scrubber, as shown and described.

DESCRIPTION

FIG. 1 is a top view of an electric spin scrubber.

FIG. 2 is a bottom view of an electric spin scrubber.

FIG. 3 is a left side view of an electric spin scrubber.

FIG. 4 is a right side view of an electric spin scrubber.

FIG. 5 is a front view of an electric spin scrubber; and,

FIG. 6 is a rear view of an electric spin scrubber.

The broken lines in the drawings are for the purpose of illustrating portions of the electric spin scrubber that form no part of the claimed design.
